UNITED STATES PATENT OFFICE.

RALPH R. HALL, OF LONG BEACH, CALIFORNIA, ASSIGNOR OF ONE-HALF TO WILLIAM A. TROUT, OF LONG BEACH, CALIFORNIA.

CORING DEVICE.

Application filed October 23, 1922. Serial No. 596,441.

This invention relates to coring devices, and particularly to a device adapted to 5 punch a given section of earth strata so that the given section which may be termed a core, may be extracted from a well hole to determine the formation and extent of materials beneath the surface. A device of this character is extensively used by contractors for testing sites for building foundations in the mining industry, which will show the character of the earth found at a great depth, as well as testing sites for docks, piers, river borings, etc. A device of this character is particularly applicable in determining the character of earth formation in drilling well holes. It is also of great value in coal regions, as accurate data may be obtained from the strata through which the bore is passing.

20 An object of this invention is to provide a device of the character stated which is easy to operate and which will extract a core with accuracy and economy and of sufficient size to procure reliable geographical data.

Various features of the invention will be set forth in a detailed description and the invention has for an object the provision of an improved coring means which will be 30 superior in point of relative simplicity and inexpensiveness, taken in conjunction with utility, durability and general efficiency and serviceability.

With the above mentioned and other objects in view, the invention consists in the novel and useful provision, formation, construction, combination, association and interrelation of parts, members and features, as illustrated in some of its embodiments in 40 the accompanying drawing, described in the following general description, and finally pointed out in claims.

In the drawing:

Figure 1 is a view partly in section of the 45 improved coring means in the act of extracting a core of earth formation;

Figure 2 is a cross sectional view of the coring device;

Figure 3 is a cross sectional view, taken 50 on the line 3-3 of Figure 2; and

Figure 4 is a fragmentary view, certain parts being in section, showing the various elements of the coring device in unassembled relation.

55 Corresponding parts in all the figures are

designated by the same reference characters.

Referring with particularity to the drawing, the improved coring means is designated in its entirety by A, of which a is a tubular drill, b a split liner receivable within the tubular drill a, and c a pin member. The pin member is formed in two sections 1 and 2, which sections are adapted to be held in co-acting relation as by means of dowel pins 3 carried by one of the sections entering recesses 4 carried in the other section. The pin c is formed with a reduced and taper screw-threaded portion 5, and this reduced taper portion 5 is adapted to have a screw-threaded engagement with a box 6 shown by dotted lines at 6 in Figure 1. This screw-threaded engagement with the box of course holds the two sections of the pin in co-acting relation. Said pin is provided with a longitudinal bore d, said bore being 75 of varying diameter at different lengths as at 7, 8 and 9. The point of juncture between the parts 7 and 8 of the bore d forms a shoulder against which an end of the split liner b is adapted to shoulder. An annular 80 groove 10 is included as between the parts 8 and 9 of the bore d and said groove is adapted to receive an annular flange 11 carried by one end of the drill a. The drill a has for a portion of its length an internal 85 tapered bore 12 and the split liner is formed with a varying external diameter adapted to fit within the tapered bore 12. A zone adjacent the working end 13 of the drill a is internally serrated as shown at 14 with the 90 open end or mouth of the said drill a beveled as shown at 15. In actual assemblage the split liner, both sections thereof, are slipped within the tapered bore 12 of the drill a until an end thereof shoulders at the point 16. The 95 pin c, both sections thereof, are then slipped around the drill a and the flange 11 of the drill will be received within the annular socket 10 of the pin, and an end of the split liners b will shoulder at the point 8 within 100 the pin. The pin member may then be screw-threaded within the box and all the parts will be held in close working assemblage. To aid in ensuring a proper cutting action, the outer surface of the drill a is 105 likewise beveled as shown at 17. Circulation openings are provided in the pin c, as shown by the dotted lines at 18 and 19.

Assuming that the improved coring means A is united to the box 6, which box in turn 110

is united to a string of tubing as D, said tubing including within its length jar members, the said tubing may be lifted a distance and then dropped, and the chisel-like end 5 of the coring means A will tend to penetrate the earth formation, as shown in Figure 1 so that the same will enter the coring means, as shown at 20; the earth formation 20 being forced within the drill will be wedged 10 by the drill and retained within the liner b, the teeth 14 of the drill preventing the core from being withdrawn from the drill and liner b. An upward movement upon the tubing will carry the core 20 with it 15 and the coring means A may be readily disassembled by unscrewing the pin e from the box, whereupon the sections of said pin will separate, and the liner b withdrawn from the drill a after which the sections of the 20 liner may be separated, giving a core of earth formation intact in every detail. A device of this character may be used with rotary drilling outfits, as well as with standard tools, and the drill a may be rotated 25 so as to cut its way into the earth formation or a core may be obtained by percussive means.

It is obvious that many changes and variations and modifications may be made in departure from the specific showing in adapting the invention to varying conditions of use and service, without departing from the 30 true spirit of the invention.

Having thus disclosed my invention, I claim and desire to secure by Letters Patent: 35

1. A pin and box, comprising separable members formed to receive and accommodate a core drill, in combination with a tubular core drill and a removable liner for the drill; the core drill being provided with an 40 inner end enlargement, and the box having a recessed portion receiving said enlargement and whereby the thrust of percussive action is transmitted from the core drill to the box. 45

2. The combination, with a stem and box; of a tubular core drill adapted to be received within the box at one end portion, and a removable liner for the box; the pin and box comprising separable portions which 50 when separated release the core drill and permit removal of the liner thereof with the core. 55

3. The combination, with a stem and box; of a tubular core drill adapted to be received within the box at one end portion, and a removable liner for the box; the pin and box comprising separable portions which when separated release the core drill and permit removal of the liner thereof with the 60 core; said liner comprising separable portions maintained in assemblage within the drill.

In testimony whereof, I have signed my name to this specification.

RALPH R. HALL.
